UNITED STATES PATENT OFFICE.

AMOS P. MILLER, OF EL DORADO, OHIO.

STRAW-STACKING ATTACHMENT FOR THRASHING-MACHINES.

SPECIFICATION forming part of Letters Patent No. 449,556, dated March 31, 1891.

Application filed October 21, 1890. Serial No. 368,777. (No model.)

To all whom it may concern:

Be it known that I, AMOS P. MILLER, a citizen of the United States, residing at El Dorado, in the county of Preble and State of Ohio, 5 have invented a new and useful Straw-Stacking Attachment for Thrashing-Machines, of which the following is a specification.

This invention relates to straw-stacking attachments for thrashing-machines; and it 10 has for its object to construct a device of this class which may be mounted transversely at the rear end of the machine, so as to carry the straw off to one side.

The invention consists in the improved 15 construction, arrangement, and combination of parts, which will be hereinafter fully described, and particularly pointed out in the claims.

In the drawings hereto annexed, Figure 1 20 is a plan view showing my improved straw-carrier attached to the rear end of a thrashing-machine. Fig. 2 is a sectional view taken transversely through my improved carrier and showing the rear end of a thrashing- 25 machine in elevation. Fig. 3 is a sectional view taken longitudinally through the carrier and looking toward the machine. Fig. 4 is a sectional view taken on the line 4-4 in Fig. 1. Fig. 5 is a plan view of the carrier detached 30 from the thrashing-machine.

Like numerals of reference indicate like parts in all the figures.

My improved straw-carrying attachment is composed of an endless carrier suitably mounted upon a trough, which is constructed in the usual manner of side pieces 11, connected by a bottom piece 2, and provided at their ends with bearings for the shafts 3 and 4, which are provided with drums or pulleys 5, supporting the endless belts 6, which are connected by slats 7. The sides of the trough may be provided with guard-rails 8, which may be readily mounted detachably in staples 9 upon the sides of said trough, the 45 guard-rails being provided with brackets or stakes 9^a, to engage the said staples, as will be seen in Fig. 2 of the drawings. One side of the trough, which in practice is nearest to the thrashing-machine, is provided with laterally-extending brackets 11, having bearings for a shaft 12, the greater portion of which is square in cross-section. Upon one end of the

shaft 12 is mounted a bevel-gear 13, meshing with a pinion 14 upon one of the shafts 4. Upon the square portion of the shaft is 55 mounted a sprocket-wheel 15, having a collar 15^a, and which may be connected by a chain 16 with a drive-wheel upon the thrashing-machine, from which motion may thus be transmitted to the endless carrier. The sprocket-wheel 15 is longitudinally adjustable upon the shaft 12, and may be retained securely at any desired adjustment by means of a set-screw 17 extending through the collar 15^a of 60 said wheel. 65

To the under side of the discharge end of the thrashing-machine is secured a horizontal arm or bracket 18, which extends rearwardly and which is connected by means of inclined braces 19 with the sides of the machine. The 70 arm or bracket 18 is provided with vertical perforations 20, through which pass the hook-bolts 21, the lower ends of which are provided with thumb-nuts 22. To adjust my improved straw-carrier in position for operation it is 75 mounted upon the arm or bracket 18 between the hook-bolts 21, which latter are caused to engage the upper edges of the side pieces of the conveyer-trough, which latter may then be firmly secured by tightening the thumb-nuts. The outer end or ends of the conveyer-trough are connected by means of ropes or 80 chains 23 with hooks 24 upon the upper side of the machine, thus bracing the carrier in position for operation and also enabling its 85 outer end to be raised when it is desired to place the carrier in an inclined position.

The discharge-chute of the thrashing-machine is provided with a bracket 25, which projects from the floor of the same rearwardly 90 over the transversely-arranged stacker, so as to deposit the straw upon the latter in any position to which it may be adjusted.

My improved transverse stacker is intended to be used as supplemental to the ordinary 95 upwardly and rearwardly inclined stacker, which latter is in practice intended to receive the chaff that may be blown out through the tail end of the machine, while the transversely-arranged stacker receives the straw and 100 carries it off to the mow or barn. The transverse stacker is intended to be arranged directly above the ordinary stacker.

The stacker which forms the subject of my

invention is capable of being adjusted transversely with relation to the machine to which it is attached, the sprocket-wheel 15 being longitudinally adjustable upon the shaft 12, 5 so that it may be readily moved to the position which it is desired to occupy.

From the foregoing description, taken in connection with the drawings hereto annexed, the construction, operation, and advantages 10 of my invention will be readily understood.

The construction of my improved stacker is simple and inexpensive, and it may be readily applied to any ordinary thrashing-machine without changing the construction of 15 the latter in any particular, except to provide it with the horizontal supporting-bracket 18, having the bolts by means of which the trough of the carrier is secured in position for operation.

20 The device is especially useful for thrashing flax and the like, where it is desirable to separate the straw from the chaff and to convey it to a separate place of deposit.

Having thus described my invention, what 25 I claim, and desire to secure by Letters Patent of the United States, is—

1. As an improvement in straw-stackers, the herein-described endless carrier, the frame of which is provided at one side with 30 laterally-extending brackets, in combination with a shaft journaled in said brackets and having a longitudinally-adjustable sprocket-wheel, and provided at one end with a bevel-gear meshing with a pinion upon the shaft 35 at one end of said endless carrier, substantially as set forth.

2. In a straw-stack for thrashing-machines, the combination of the frame consisting of side pieces connected by a suitable bottom piece, the shafts journaled at the ends 40 of said side pieces and having drums or pulleys, the endless bands mounted upon the latter and connected by transverse slats, the guard-rails having stakes adapted to engage staples upon the side pieces, brackets extending laterally from the latter, a shaft journaled in said brackets and having a longitudinally-adjustable sprocket-wheel, and a bevel-gear mounted upon one end of said shaft and meshing with a pinion upon the 45 shaft at one end of the frame, substantially as set forth.

3. The combination, with a thrashing-machine having a rearwardly-extending arm or bracket, of a straw-stack mounted adjustably upon said bracket transversely to the thrashing-machine, the bolts 21 and chain 23 for securing the said stacker-frame adjustably upon the said bracket, and a sprocket-wheel mounted adjustably upon the drive-shaft of the carrier and adapted to receive motion from the thrashing-machine, substantially as set forth.

In testimony that I claim the foregoing as my own I have hereto affixed my signature in 65 presence of two witnesses.

AMOS P. MILLER.
